UNITED STATES PATENT OFFICE

162,627

AIR CIRCULATOR

Samuel B. Camiel, New York, N. Y., assignor to
Circulators & Devices Mfg. Corp., Brooklyn,
N. Y., a corporation of New York

Application July 11, 1950, Serial No. 11,070

Term of patent 14 years

(CL. D26—7)

To all whom it may concern:

Be it known that I, Samuel B. Camiel, a citizen of the United States of America, and resident of the county of Kings, city and State of New York, have invented a new, original, and ornamental Design for an Air Circulator, of which the following is a specification, reference being had to the accompanying drawing forming a part thereof, in which

Fig. 1 is a top plan view of an air circulator embodying my new design;

Fig. 2 is a front view thereof; and

Fig. 3 is a bottom view thereof.

I claim:

The ornamental design for an air circulator, as shown.

SAMUEL B. CAMIEL.
